UNITED STATES PATENT OFFICE.

JOHN MAGNUS LARSSON SPANGENBERG, OF FORSHAGA, SWEDEN.

SORTER FOR PAPER-PULP AND THE LIKE.

1,163,275.

Specification of Letters Patent.

Patented Dec. 7, 1915.

Application filed January 18, 1915. Serial No. 2,950.

To all whom it may concern:

Be it known that I, JOHN MAGNUS LARSSON SPANGENBERG, civil engineer, subject of the King of Sweden, residing at Forshaga, 5 in the Kingdom of Sweden, have invented certain new and useful Improvements in Sorters for Paper-Pulp and the like, of which the following is a specification.

The present invention relates to such 10 sorters for paper pulp and the like which consists of a cylinder rotatably arranged in a receptacle, the side walls of said cylinder consisting of a perforated mantle through which the fibers pass from without inward, 15 and the interior of which is in communication with a suction or exhaust pipe and which sorters are provided with members movable within the said cylinder serving to cause a momentary change in the direction 20 of flow of the current to prevent the holes in the mantle or casing being clogged by fibers and the like.

In previously known devices for this purpose the said members arranged within the 25 cylinder have been constructed as longitudinal vanes supported by a shaft rotatably arranged within said drum. In accordance with the present invention on the contrary the said member consists of a longitudinal body or drum eccentrically arranged within the said cylinder, which body or drum in cross section has a polygonal form with straight or curved sides and eventually also rounded corners. And further, 30 stationary longitudinal blades are arranged in the space between the mantle of the perforated drum and the stirring member. By this arrangement a better effect is gained than with the apparatuses of the same type 35 before known.

In the accompanying drawing is illustrated by way of example a form of construction of the invention, used in an apparatus of the kind described in my United 40 States Patent No. 1042724.

Figure 1 is a longitudinal section of the apparatus, and Fig. 2 shows the same in cross section along the dotted line in Fig. 1. Fig. 3 shows in cross section diagrammatically other modified forms of the stirring member.

In the different figures similar parts are indicated with the same characters of reference.

The invention is first described with reference to Figs. 1 and 2.

The sorter consists of a straining drum 4 rotating in the well known manner in a receptacle 3 provided with an inlet opening 1 for the material to be treated, consisting 5 of pulp suspended in water, and a suction exit 2. The circumference of said drum 4 consists of a mantle of perforated plate or metal wire tissue. Within the said drum 4 are arranged the above-mentioned stirring 10 member for producing changes in the direction of current, which member, according to the form of construction shown in the drawing, consists of a longitudinal drum or body of polygonal for instance pentagonal cross 15 section mounted on a rotatable shaft 9. The shaft 9 can be arranged concentrically with the axis of the drum 4, as shown in Fig. 3, but according to the form of construction illustrated in the other figures on the drawing it is arranged eccentrically in relation to the axis of the drum, in order to provide a space between the rotating vanes 7 and the mantle or casing of the drum 4 at the top 20 of the same for a spurt pipe 10 arranged 25 within the drum, which pipe 10 at its upper side facing the casing of the drum is provided with a number of apertures or perforations, so that when water is supplied to the said pipe 10 through the inlet 11, the 30 water spurts out in a fine spray against the perforated mantle of the drum, whereby the perforations in said mantle are free from fibers and the like fastened in it. Within 35 the drum 4 longitudinal blades 32 are arranged by which the space between the perforated mantle of the drum 4 and the stirring member 7 is subdivided in several sections, whereby the desired effect of the rotation of the body 7 will be increased.

According to Figs. 1 and 2 one such blade is arranged on each side on the pipe 10 and fastened to the end wall 33 of the receptacle 3 and projecting into the drum 4 in the same way as said pipe 10. For rotating the 40 drum 4 and the stirring member 7 which may be rotated in the same or in opposite direction, means of any suitable construction may be used, which however do not form object for the present invention. By way of 45 example I will in the following describe a form of said driving means as described and illustrated in my earlier United States Pat-

- ent No. 1,042,724. The drum 4 is at one of its ends provided with a hollow axle-journal 12, which axle-journal 12 passes through the end of the receptacle 3 and is rotatably carried by bearings 13. In order to bring about a tight fit between the said shaft and the end wall of the receptacle 3, packing devices 14 of some suitable construction are provided.
- 10 At the opposite end the prolonged part 14 of the drum 4 is rotatably carried by wooden blocks 16 or the like arranged in the receptacle 3. The shaft 9 passes through the hollow axle-journal 12 and is rotatably carried 15 at this end by a bearing 17 and at the opposite end said shaft is journaled in a bearing 18.

For driving the shaft 9 and the stirring member 7 carried by it, there is arranged at 20 one end of the shaft 9 a belt-pulley 19, which is set in rotation in the usual manner by means of a belt (not shown). The drum 4 is also driven from the said shaft by means of a toothed wheel 20 mounted on the shaft 25 9, which toothed wheel 20 engages with a toothed wheel 21, mounted on one end of a rotatable shaft 22, on the other end of which shaft 22 there is a toothed wheel 23 engaging with a toothed wheel 24 mounted on the 30 axle-journal 12 of the drum. The gearing is arranged in such a manner that the shaft 9 rotates at a comparatively great speed, *e. g.* 35 80 revolutions per minute, while the drum 4 rotates comparatively slowly, *e. g.* 4 revolutions per minute.

In order to bring about a tight fit of the outer end of the hollow axle-journal 12 there is a ringshaped disk 25 tightly mounted on the shaft 9, which disk 25 is pressed against 40 the end of the said axle-journal by means of a ring 28 and springs 26 fitted onto the screw-bolts 27, which screw-bolts 27 are at one of their ends screwed into the nave of the wheel 24 and at their other ends are provided with nuts, between which nuts and the ring 28 the springs are located. The said 45 springs press against the ring 28, which ring 28 bears against and slides on the disk 25 and presses the latter against a packing-50 ring 29 arranged between the end of the axle-journal and the disk 25. As will be obvious from the above, the ring 28, through its connection with the screw-bolts 27, takes part in the rotation of the drum, while on 55 the other hand the disk 25 is prevented from taking part in the said rotation by means of an arm 31 engaging with it, which arm 31 is attached to the standard 30 supporting the bearing of the shaft 9. In this way the 60 open axle-journal 12 is tightly closed in spite of the fact that the rotating shaft 9 passing through it is eccentrically located in relation to the same. As the other parts of the apparatus do not relate to this inven-

tion, a description of them and the manner 65 in which the apparatus otherwise is shown adapted to an apparatus of previously known type.

In Fig. 3 is shown by way of example in full line the cross sections 7" of a stirring 70 member, the sides of which are convex and in the same Fig. 3 is shown with dotted lines a form of stirring member 7'", the sides of which are concave.

It may be understood that a stirring member 75 of any polygonal cross section may be used, the above stated forms being described and illustrated only by way of examples.

The device in question works in the following manner: While the fibers or paper 80 pulp deposited in the water, which nearly completely covers the straining drum, is being sucked through the perforated walls of the slowly rotating drum 4, the shaft 9 and the stirring body 7 rotate at a comparatively 85 high speed. Hereby are brought about by the stirring body a change in the direction of flow of the liquid, *i. e.* there is as the member 7 rotates brought about a flow of the current from within to without alternately 90 with the normal flow from without to within, whereby a stoppage of the openings of the perforated walls of the drum is prevented.

Having thus described my invention, I 95 declare that what I claim is:

1. In an apparatus of the class described, a receptacle, a perforated drum, rotatably arranged in the same, through which drum the mass passes in the direction from without inward, a stirring member arranged within said drum, means for rotating said drum, and means for rotating the stirring member, said stirring member consisting of a longitudinal body, the cross section of 100 which has the form of a polygon, said stirring members being arranged eccentrically with the axis of the perforated drum.

2. In an apparatus of the class described, a receptacle, a perforated drum, rotatably arranged in the same, through which drum the mass passes in the direction from without inward, a stirring member arranged within said drum, means for rotating said drum and means for rotating the stirring 110 member, said stirring member consisting of a longitudinal body, the cross section of 115 which has the form of a polygon, longitudinal blades being arranged at intervals in the space between the mantle of the perforated 120 drum and the stirring member, said blades being stationary.

3. In an apparatus of the class described, a receptacle, a perforated drum, rotatably arranged in the same, through which drum the mass passes in the direction from without inward, a stirring member arranged within said drum, means for rotating said 125

drum and means for rotating the stirring member, said stirring member consisting of a longitudinal body, the cross section of which has the form of a polygon, said stirring members being arranged eccentrically with the axis of the perforated drum, longitudinal stationary blades being arranged in the upper part of the space between the perforated drum and the stirring member,

said blades being fastened to one end of the receptacle and projecting into the drum.

In witness whereof I have hereunto set my hand in presence of two witnesses.

JOHN MAGNUS LARSSON SPANGENBERG.
